DRIP PAN FOR FLUSH TANKS

Clifford J. Wanke, Janesville, Wis.

Application June 17, 1948; Serial No. 33,459

1 Claim. (Cl. 4-252)

1

My invention refers to drip-pans for flush tanks and it has for its primary object to provide a pan having adjustable seats for the supply and flush pipes of a tank, whereby compensation is had for variations that are found in the position of said pipes with reference to the tank bottom.

The three point suspension set bolt attaching means for the pan to the flush pipe is similar to that shown in my co-pending patent application #8,380, dated February 14, 1948.

The specific object of my present invention is to provide compensating plates for the pipe openings in a pan, whereby the supply pipe may be boxed, irrespective of its lateral or transverse position, with reference to the tank bottom, and an anchor boxing plate assemblage for the flush pipe, irrespective of its transverse position relative to said tank bottom.

A further object of my invention is to provide a transversely adjustable boxing plate for the flush pipe associated with the pan, having three point suspension radially disposed bolts for anchoring said pan.

With the above and other objects in view, which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Fig. 1 represents a sectional elevation of a drip-pan attaching means to a tank flush pipe, embodying the features of my invention, the section being indicated by line 1-1 of Figs. 2 and 3 of the drawings.

Fig. 2 is a longitudinal sectional view through the same, the section being indicated by line 2-2 of Fig. 3.

Fig. 3 is a plan view of the same, partly in section as indicated by line 3-3 of Fig. 2; and

Fig. 4 is a detail cross sectional view through the boxing assemblage of the flush pipe, the section being indicated by line 4-4 of Fig. 3.

Referring by characters to the drawings, A indicates a flush tank, having depending from its bottom a flush pipe B and a supply pipe C.

Anchored under the bottom of the tank is an

2

upstanding ribbed drip-pan 1, having a ribbed or flanged slotted opening 2, extending from one edge thereof and associated with the supply pipe C, the said opening being of a materially greater cross sectional area than the pipe.

A second upstanding U-shaped flanged opening 3 also extends from the rear edge of the pan and its edge flange terminates with an inwardly extended wing 4, having a curved throat about the flush pipe and straight leg extensions therefrom.

The wing extensions are formed with slots 5 and fitted over said wing extensions is a boxing plate 6, the same having downturned flanges 6', which engage the flanges of the associated pan opening and said boxing plate is formed with an open throat extending inwardly from its rear edge terminating in an enlarged circular opening. An upturned flange 7 extends about the circular edge of the opening.

The upturned flange 7 carries a centrally positioned upstanding ear 7', which adjustably receives a threaded set bolt 8. Depending from the walls of the circular opening adjacent to the throat and on opposite sides of the ear 7' are ears 9 and these ears adjustably receive threaded set bolts 10. The bolts 10 in conjunction with the set bolt 8 form a three-point suspension anchor for the pan, the bolts being threaded into tight engagement with the flush pipe B.

The boxing plate 6 carries a pair of depending bolts 11, which bolts pass through the wing slots 5 and are secured by thumb nuts, whereby the pan can be adjusted backwardly and forwardly.

As best indicated in Figs. 2 to 4 inclusive, the throat portion of the boxing plate is fitted with an adjustable extension plate 12, having downturned edge flanges in slidable engagement with the throat portions of the boxing plate.

The adjustable extension plate 12 is also provided with an upstanding circular flanged recess 12', which recess, when the parts are in position, completes the circular throat recess of the boxing plate. This extension plate 12 serves to close up the rear portion of the opening 3 and if said extension plate is not of sufficient length, a second extension plate 13 may be lapped over the same and in slidable union therewith.

Thus the depth of the flush tank drip-pan opening is adjustable, whereby said opening is closed from end to end. Due to the transverse adjustment of the boxing plate, the position of the flush pipe is accommodated for the three point anchor means.

Referring to the slotted opening 2 of the drip-

pan, which is associated with the supply pipe C, I provide a boxing plate 14, having downturned flanges which are spaced from the flanges of the opening 2, and also said boxing plate is provided with a throat 15, having an upturned flange, which is centered about the supply pipe. By employing a boxing plate of this type, it will be noted that it may be adjusted longitudinally and also laterally, whereby it will properly jacket the supply pipe C, irrespective of its position, with reference to the flush pipe.

In some instances the throat of the boxing plate 14 may be provided with a laterally disposed strip, not shown, for closing the throat opening.

It will be noted, as illustrated in Fig. 1 of the drawings, that the pan is of standard type and is slightly forwardly inclined and provided with a drain nipple D.

It is to be noted that the pair of set bolts engaging the flush pipe are shown in a different plane from the companion single set bolt, whereby due to the obliquely disposed grip upon the flush pipe there is little tendency for slippage of the drip-pan.

While I have specifically defined structural details, it is understood that I may vary the same within the scope of the claim.

I claim:

A drip-pan for flush tanks having an open pipe receiving slot extending inwardly from one edge thereof, the edges of said slot being provided with an upstanding flange having an inwardly extending wing, said wing being provided with longitudinally extending slots, a boxing plate fitted over the wing and having opposite down-turned

5
10

flanges engaging the flange of the slot in the pan and a flat surface having an open throat extending inwardly from the rear edge thereof and terminating in an enlarged circular opening, an upstanding flange surrounding the circular edge of the opening for engaging about a pipe, an upstanding centrally disposed ear carried by the flange, a set bolt carried by said ear, a pair of depending ears disposed on each side of the central ear adjacent to the front of the circular opening at the junction with the throat and carried by the sides of the opening, set bolts carried by said pair of ears for engaging a pipe below the first mentioned set bolt, and thumb nuts and bolts carried by said boxing plate and received in the slots of the wing, whereby the pan can be adjusted back and forth on the boxing plate.

CLIFFORD J. WANKE.
